C. T. WALTERS

ROD PACKING

Filed Sept. 25, 1919.

Fig. 4

Inventor,
Charles T. Walters

by H. S. Johnson
his Attorney.

UNITED STATES PATENT OFFICE.

CHARLES T. WALTERS, OF ST. PAUL, MINNESOTA.

ROD PACKING.

Application filed September 25, 1919. Serial No. 326,359.

To all whom it may concern:

Be it known that I, CHARLES T. WALTERS, a citizen of the United States, residing at St. Paul, in the county of Ramsey and State 5 of Minnesota, have invented certain new and useful Improvements in Rod Packings, of which the following is a specification.

This invention relates to metallic packing devices for piston rods and the like, and 10 more particularly to that type of packing devices used on reciprocating rods wherein it is difficult to keep the rod in alignment with the gland in the stuffing box, such as the piston rod of a locomotive which constantly vibrates laterally owing to the wear 15 of the piston in the bore of the cylinder.

An object of the invention is to provide metallic packing means which may be quickly 20 and conveniently replaced and which is adapted to utilize the steam pressure in the cylinder to assist in pressing the metallic packing against the piston rod as an additional safe guard against leakage.

A still further object of the invention is 25 to provide improved metallic packing means so constructed as to be capable of being preliminarily assembled on the rod and then bodily projected into the stuffing box chamber of the cylinder head.

A still further object of this invention is 30 to provide an improved rod packing construction whereby a permanent and effective steam tight joint may be maintained under all conditions regardless of lateral vibration 35 on the rod and at the same time provide at a point outside of the metallic packing, lubricating means surrounding the rod to further assist in sealing the joint against leakage.

To this end the invention consists in the 40 construction, combination and arrangement of parts hereinafter described and claimed.

In the accompanying drawings forming 45 part of this specification;

Figure 1 is a vertical longitudinal section 50 through the stuffing box of a cylinder head showing the invention applied thereto.

Figure 2 is a perspective view of the invention.

Figure 3 is a side view of the same showing 55 the parts partly disassembled.

Figure 4 is a sectional view on line 4-4 of Figure 3, and

Figure 5 is a front view of the metallic packing ring.

In the drawings, A represents a cylinder

head formed centrally with an outwardly projecting stuffing box member B, the bore or stuffing box chamber C thereof being of uniform diameter.

Concentric with the stuffing box chamber is the bore D adapted to loosely receive the piston rod E, the bore being sufficiently large to permit the piston rod to vibrate laterally concurrently with its reciprocatory movement.

The stuffing box chamber C may be of any standard size, it being one of applicant's objects to provide packing means that may be applied to locomotive cylinders of different types now in use.

The invention comprises a composite casing F, adapted to contain my improved packing, the casing being formed of two members, the outer member thereof being preferably exteriorly rectangular in contour and having two parallel faces 2 and 3, the latter being formed with an annular recess 4 adapted to receive the flange 5 which flange forms the outer end of a cylindrical casing member 6 the latter having at its inner end the inturned flange 7, the casing 6 together with said flanges forming the inner casing member of the casing F.

The bore 8 at the inner end of the inner casing member is considerably larger in diameter than the rod E, the inner face 9 of the flange 7 being disposed in a transverse plane perpendicular to the longitudinal axis of the rod. The casing 6 as shown in the drawings extends approximately the full depth of the chamber C, the flange 5 being flush with the face 3 of the outer member and being formed on its underface with an annular groove adapted to register with a similar groove in the outer face of the stuffing box member B so as to receive the soft metal gasket G whereby the joint between the stuffing box and the casing is rendered tight, the outer member being provided with bolt holes 10 to receive the cap screws 11 having screw threaded engagement with the stuffing box member whereby the casing and the latter may be firmly clamped together.

The wall of the inner casing member is of thin metal construction to enable the forming an annular chamber 12 around the piston rod, the chamber 12 communicating with the counterbore 13 in the face 3 of the outer casing member.

The counterbore 13 extends approximately

half the depth of the outer casing member, the latter having a central bore 14 similar to the bore 8 of the inner casing member, the bottom 15 of the counterbore 13 being parallel with the face 9 of the flange 7. The outer face 2 of the outer casing member is counterbored to form the annular chamber 16 and a recess to receive the annular clamping ring 17, the latter loosely surrounding the piston rod and being held positioned by means of screws 18 screw threaded in the outer casing member. The clamping ring when positioned is flush with the face 2 and is arranged relative to the bolt holes 10 so that the heads of the cap screws 11 will overlap the latter as shown in Figure 2. In the chamber 16 are a pair of comparatively thin washers 19 embracing between them, a wick-like substance I adapted to absorb lubricating oil which may be supplied through the duct 20 in the outer casing member.

In the annular space formed between the chamber 12 and the counterbore 13 are two oppositely disposed spaced elements H surrounding the piston rod and contacting flatly respectively with the faces 9 and 15 of the inner and outer casing members. In the space between the elements and surrounding the rod is the coil spring 21 engaging said elements at their respective ends and tending constantly to separate them to press said elements against said faces 9 and 15 respectively. Each of said elements comprises a floating ring 22 having two parallel flat faces and formed peripherally with a shoulder 23, said ring fitting slidably around the piston rod; a follower ring 24 loosely surrounding the piston rod and formed with a peripheral off-set or shoulder 25 to receive and hold centered said coil spring, and having an interiorly tapered or conical surface of about forty-five degrees bevel and adapted to engage and fit over the conic surface of a soft metal packing ring 26, the opposite face of the latter fitting flatly against the ring 22. As shown in Figure 5 the packing ring is formed of two segments.

All of the rings are smaller in diameter than the interior of the member 6 so as to afford steam space for the purpose of intercepting any leakage of steam that may find its way past the ring 22 of the packing element nearest the cylinder. Obviously, the follower rings 24 being constantly under compression of the spring 21 tend to crowd the soft metallic packing rings against the reciprocating piston rod E, the bores 8, 14 and D being sufficiently large to permit the rod to vibrate laterally. The packing elements H are carried bodily with the rod in

its lateral vibrations and the meeting surfaces of the rings with the faces 9 and 15 respectively slide upon one another and form a ground fit.

If, however, the pressure in the cylinder should at any time exceed the pressure of the spring 21 and enter the chamber 12 the ring 22 farthest removed from the cylinders under the influence of the pressure of the steam would be forced against the face 15 and prevent further leakage.

When it is desired to examine the packing the bolts 11 are removed and the outer casing member is slid along the rod, as indicated in Figure 3, the casing and the inner packing element remain intact. By inserting a screw driver between the end of the stuffing box and the flange 5, the casing may be withdrawn from the stuffing box chamber C, both packing elements being thereby brought in full view to be examined or replaced.

This arrangement affords a quick and convenient way of extracting the packing element from within the chamber C. A further advantage lies in the fact that the composite casing together with the spring and packing elements may be conveniently wired together to form a compact package so desirable in cases where large quantities are stored in bins.

I claim:

In a rod packing, the combination with a piston rod, and a stuffing box, said stuffing box including a chamber; of a thin shell-like casing member extending freely into said chamber approximately the full length thereof, said casing member having an in-turned flange at its inner end spaced from the piston rod, and being formed exteriorly with an annular shoulder designed to overlap the surrounding wall of said chamber, an outer member formed with a counterbore, spaced from the piston rod and adapted to be bolted to said chamber and over said shoulder and clamping said shoulder between itself and the wall of said chamber, said counterbore forming an extension of said stuffing box chamber, and oppositely disposed rod packing elements partly located within said casing and surrounding the piston rod from said inturned flange to the bottom of said counterbore, said oppositely disposed packing elements being held separated by an extensible coil spring surrounding the piston rod, for the purpose set forth.

In testimony whereof I affix my signature.

CHARLES T. WALTERS.
